DESIGN FOR A DRESS

Pauline Fracchia, New York, N. Y.

Application April 12, 1939, Serial No. 84,215

Term of patent 3½ years

To all whom it may concern:

Be it known that I, Pauline Fracchia, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination on the specific striped dress disclosed of the rows of wide shirring on the shoulders and at the waistline in association with the narrower rows of shirring above the girdle sash and on the sleeves, said shirring constricting the stripes of the dress fabric as shown.

I claim:

The ornamental design for a dress, substantially as shown and described.

PAULINE FRACCHIA.
